UNITED STATES PATENT OFFICE.

THOMAS LEGGETT STURTEVANT, OF QUINCY, AND THOMAS J. STURTEVANT, OF WELLESLEY, MASSACHUSETTS.

MECHANICAL FEEDING DEVICE.

SPECIFICATION forming part of Letters Patent No. 758,119, dated April 26, 1904.

Application filed January 9, 1904. Serial No. 188,290. (No model.)

To all whom it may concern:

Be it known that we, THOMAS LEGGETT STURTEVANT, residing at Quincy, and THOMAS J. STURTEVANT, residing at Wellesley, in the county of Norfolk and State of Massachusetts, citizens of the United States, have invented certain new and useful Improvements in Mechanical Feeding Devices, of which the following is a specification, reference being had therein to the accompanying drawings.

This invention relates to an improved automatic device for feeding materials to be pulverized, screened, or otherwise acted on mechanically to machines of various kinds; and the invention comprises certain improvements on the feeding device shown and described in our Patent No. 592,698, granted July 10, 1894.

In the accompanying drawings, Figure 1 is a side view of the improved feeding device with the internal construction indicated in dotted lines, and Fig. 2 is a perspective view of the same on a somewhat smaller scale than Fig. 1. Fig. 3 is a vertical sectional view of the feeding device and its operating mechanism.

Referring to the drawings, 12 denotes a casing adapted to serve as a hopper and also as a housing for the internal parts of the feeding mechanism. The casing 12 is provided with suitable projections 13, serving as bearings for a shaft 14, provided with a driving-wheel 15 and with an eccentric 16. Within the casing 12 are inclined webs or partitions 17 and 18, which, with the sides of the said casing, form a chamber or hopper for the reception of the material to be fed. Below the hopper portion of the casing is an inclined and end-wise reciprocating or swinging pan or chute 19, the lower end of which is supported by a link or arm 20, while the upper part of the said pan or chute is supported by the upper arm of a bell-crank rocker 21, pivotally mounted in a lug 22 of the casing, and the lower arm of which is provided with a wheel or roller 23, held by a spring 24, engaging the upper end of the swinging pan or chute against the eccentric 16. The stress of the spring 24 may be regulated or varied by a set-screw 25, tapped in a lug in the casing 12 and bearing

against a follower 26 at one end of said spring, 50 and the said set-screw may be secured in any desired position of adjustment by a lock-nut 27.

The output of the feeding device may be regulated by a gravitating swinging gate 28, 55 provided with an arm 29, pivoted at 30 to the casing 12, and having a shorter arm 31, engaged by a regulating-screw 32, tapped in a lug in the said casing 12, and provided with a set-nut 33, by which it may be held in any 60 desired position of adjustment.

The casing 12 is preferably provided with a removable end plate or cover 34 for an opening, through which access may be had to the interior of the casing at the feed-gate end 65 thereof.

From the foregoing it will be understood that the improved feeding device is self-contained, in that it is provided with a driving-shaft mounted on the casing thereof and provided with an eccentric from which and a co-acting spring the swinging feed-pan can be operated, the feeder as a whole being adapted for attachment to any crushing, pulverizing, screening, or other machine suitably constructed for its reception. By mounting the swinging feed pan or chute on a link and an operating rocker-arm, as shown, the said swinging pan or chute will be strongly supported on nearly frictionless bearings, so that the wear incident to the operation of the device will be reduced to a minimum, while the output of the feeder may be regulated to a nicety by the adjustable gravitating feed-gate 28. 75

Having thus described our invention, we claim and desire to secure by Letters Patent—

1. In a feeding device, the combination with an inclosing casing adapted to serve as a hopper, of a rotating shaft mounted on said casing and provided with a driving-pulley and an eccentric, a swinging pan or chute below the hopper portion of said casing, a link, 20, movably supporting one end of said pan or chute, a bell-crank rocker, 21, the upper arm 90 of which is pivotally connected with said pan or chute and the lower arm of which is provided with a roller 23, a driving-shaft 14 pro-

vided with an eccentric 13, and a spring 24 acting on said pan or chute and serving to hold said roller in contact with said eccentric.

2. In a feeding device, the combination with 5 an inclosing casing adapted to serve as a hopper, of a rotating shaft mounted on said casing and provided with a driving-pulley and an eccentric, a swinging pan or chute below the hopper portion of said casing, a link, 20, 10 movably supporting one end of said pan or chute, a bell-crank rocker, 21, the upper arm of which is pivotally connected with said pan or chute and the lower arm of which is provided with a roller 23, a driving-shaft provided with an eccentric and 15 a spring bearing against one end of said pan or chute and serving to hold said roller against said eccentric, and means for regulating the stress of said spring.
- 15 3. The combination with the casing 12 the 20

upper portion of which is adapted to serve as a hopper, of a swinging pan or chute mounted in the said casing below the hopper portion thereof, a link by which one end of the said pan or chute is supported, a bell-crank rocker, 21, the upper arm of which is pivotally connected with said pan or chute and the lower arm of which is provided with a roller, 23, a driving-shaft provided with an eccentric and a spring bearing against one end of said pan 30 or chute and serving to hold said roller against said eccentric, and means for regulating the stress of said spring.

In testimony whereof we affix our signatures in presence of two witnesses.

THOMAS LEGGETT STURTEVANT.
